US0D1042399S

(12) **United States Design Patent** (10) Patent No.: **US D1,042,399 S**
(45) Date of Patent: ** Sep. 17, 2024

(54) **WIRED HEADSET**

(71) Applicant: **Suya Chang**, Henan (CN)

(72) Inventor: **Suya Chang**, Henan (CN)

(**) Term: **15 Years**

(21) Appl. No.: **29/875,641**

(22) Filed: **May 8, 2023**

(51) LOC (14) Cl. **14-01**

(52) U.S. Cl.

USPC **D14/206**; D14/226

(58) **Field of Classification Search**

USPC D14/206, 226, 205, 225; D29/112; 2/209; 381/380-381, 374

CPC H04R 25/00; H04R 25/02; H04R 1/10; H04R 1/02; H04R 1/1066; H04R 1/1016; H04R 5/033; H04R 5/0335; H04R 1/1083; H04R 1/1091; H04R 19/02

Primary Examiner — Paula Allen Greene

(57) **CLAIM**

The ornamental design for wired headset, as shown and described.

DESCRIPTION

FIG. 1 is a front perspective view of a wired headset showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof.

1 Claim, 8 Drawing Sheets
